ATTY.

UNITED STATES PATENT OFFICE.

GEORGE E. CURTISS, OF NEW BRITAIN, CONNECTICUT, ASSIGNOR TO LANDERS, FRARY & CLARK, OF NEW BRITAIN, CONNECTICUT, A CORPORATION.

DESIGN FOR A HEATER FOR COFFEE, TEA, AND WATER.

45,184.

Specification for Design.

Patented Feb. 3, 1914.

Application filed September 25, 1913. Serial No. 791,866. Term of patent 14 years.

To all whom it may concern:

Be it known that I, GEORGE E. CURTISS, a citizen of the United States, residing at New Britain, in the county of Hartford and State of Connecticut, have invented a new, original, and ornamental Design for a Heater for Coffee, Tea, and Water, of which the following is a specification, reference being had to the accompanying drawing, forming part thereof.

Figure 1 is a front elevation of a heater illustrating my new design. Fig. 2 is a plan view of the same.

I claim:

The ornamental design for a heater for coffee, tea and water, as shown.

GEORGE E. CURTISS.
